FLARE CONTAINER

Filed March 10, 1934

UNITED STATES PATENT OFFICE

2,000,055

FLARE CONTAINER

Samuel Wiley, Metuchen, N. J.

Application March 10, 1934, Serial No. 714,937

4 Claims. (CL. 102—24)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a flare container.

The purpose of this invention is to provide a container having a detachable cover controlling the launching of a flare within the container.

10 Another object of the invention is to provide means whereby a powder charge forcibly removes the cover and ignites a delay charge carried by the flare within the container.

With the foregoing and other objects in view, 15 the invention resides in the novel arrangement and combination of parts and in the details of construction hereinafter described and claimed, it being understood that changes in the precise embodiment of the invention herein disclosed 20 may be made within the scope of what is claimed without departing from the spirit of the invention.

A practical embodiment of the invention is 25 illustrated in the accompanying drawing, wherein:

Fig. 1 is a view in elevation and partly in section of the improved flare and container.

Fig. 2 is a top plan view of Fig. 1.

Fig. 3 is a bottom plan view of Fig. 1.

30 Fig. 4 is an enlarged sectional view through the detachable cover.

Figs. 5 and 6 are fragmentary views similar to Fig. 4 and showing modifications of the joint of the cover.

35 The flare consists of a body of a combustible signaling or illuminating composition 5 disposed in a casing 6 which is connected by means of a cord 7 to a parachute 8. A first fire charge 9 is disposed at the lower end of the composition 5 and is ignited from a plurality of priming charges 10—10. The lower end of the casing 6 is closed by a cap 11 which carries a cup 12 containing a delay powder pellet 13.

The foregoing elements of the flare are 45 closed in a container 14 which serves as a shipping carton and also as a launching tube. The container is provided with a hook 15 whereby it is supported in a vertical position in an aircraft with its lower portion projecting below the floor 16 of the aircraft.

50 The upper end of the container 14 is closed by a permanently attached cover 17.

Referring to Fig. 4 a ring 18, angled in cross-section, is secured to the lower end of the container by rivets 19 and cooperates with the

margin of the container in providing an annular chamber 20 for containing a charge 21 of black powder.

A cover 22 closing the lower end of the container and supporting the flare is formed with a channeled marginal portion 23 closing the annular chamber 20 and is detachably secured to the ring 18 by crimping or staking as indicated at 24. The cover 22 carries a thimble 25 fitting over the cup 12. A conduit 26 leads from the thimble to the channeled portion 23 of the cover and a quick-match 27 in the conduit provides an ignition relay from the powder charge 21 to the delay pellet 13.

5 A tube 28 attached to the container 14 and 15 extending through the ring 18 and into the chamber 20 carries an electrical igniting device. The igniter consists of a small squib or tubular case filled with powder as indicated at 29 and a pair of wires 30—30 leading from the squib to a 20 source of electric current 31 and including a switch 32.

When the switch is closed to allow current to be passed through the wires 30, the squib 29 is exploded and ignites the powder charge 21, 25 and the quick-match 27 which relays ignition to the delay pellet 13. The gases from the charge 21 forcibly remove the cover 22 from the container and the flare drops out of the container under the influence of gravity. The parachute opens and suspends the illuminating composition 5 which is ignited after a proper time interval by the delay pellet 13.

In order to take up the shock of recoil of the container 14 when the charge 21 is fired, the 35 ring 18 is preferably supported against the floor 16 of the aircraft.

In the modification shown in Fig. 5 the detachable cover 33 is formed with a channeled marginal portion 34 fitting in an annular channel formed by the lower end 35 of the container and a ring 36 secured thereto.

40 In the modification shown in Fig. 6 the container 37 is closed by a plate 38 fitting over and if desired secured to a cap 39 closing the lower end of the illuminant casing 40. The plate 38 is formed with a flange 41 extending over a ring 42 fixed exteriorly to the container 37. A plate 43 having a channeled portion 44 which cooperates with the flange 41 to provide a powder 45 chamber 45 is formed with an apron 46 as at 47 over the ring 42. When the plate 43 is removed the illuminant casing 40 is free to fall 50 out of the container 37.

55

All joints are sealed with a waterproof cement.
I claim:

1. A container having an annular chamber at its lower end, a powder charge in said chamber, a detachable cover closing the lower end of the container and said chamber and adapted to be forcibly removed from the container on combustion of the powder charge, a thimble carried by the cover, a quick-match leading from the thimble to the powder charge, means for igniting the powder charge, a combustible member within the container and supported by the cover, and a delay charge carried by said member and disposed in the thimble of the cover.
- 15 2. A container having an annular chamber at its lower end, a powder charge in said chamber, a detachable cover closing the lower end of the container and said chamber and adapted to be forcibly removed from the container on combustion of the powder charge, a combustible member within the container and supported by the cover, a delay charge carried by said com-

bustible member, and means for igniting the powder charge and delay charge.

3. A container, a powder charge at the lower end thereof and separated from the contents of the container so as not to react thereupon, a detachable cover for said lower end of the container adapted to be forcibly removed on combustion of the powder charge, a combustible member within the container and supported by the cover, and a delay pellet carried by said member and receiving ignition from the powder charge.

4. A container, a powder charge at the lower end thereof and separated from the contents of the container so as not to react thereupon, a detachable cover for said lower end of the container adapted to be forcibly removed on combustion of the powder charge, and an article within the container and supported by the cover, said article free to fall out of the container when the cover is removed.

SAMUEL WILEY.
